(57) **CLAIM**

The ornamental design for a glove, as shown and described.

DESCRIPTION

1.1 is a front elevation view of a glove, showing the design. The broken line boundary defines the outer limit of the claimed design, which is limited to a portion of the front of the glove. All features within the broken line boundary are claimed elements of the design, whereas all features at and outside the broken line boundary form no part of the claimed design. The left side, right side, top, bottom, and rear of the glove form no part of the claimed design.
